UNITED STATES PATENT OFFICE.

FRED MATHEWS, OF CHICAGO, ILLINOIS.

GEARING.

Application filed November 23, 1925. Serial No. 70,881.

My present invention relates to gearing and has more particular reference to a structure that may be employed where it is desired to provide a gearing having an initial operating speed of the driven gear element that is rapid and thereafter said driven element will rotate at a uniform or fixed speed.

I have provided a gearing that may be readily employed for a railway car brake so that when the gearing is operated to apply the brake there will be a quick take-up of the pull or winding chain at a high speed ratio where little power is required and subsequently the ratio is so changed to a slower speed but at considerably increased power so that the brakes are applied to the car wheels with sufficient friction to stop the car. Of course the structure I have devised may be applied to other uses without altering the principles, hence I do not restrict myself to a gearing as applied to a brake or the like.

This gearing is especially adapted for use when the driving and driven shafts or spindles have their axis disposed at an angle to each other (preferably a right angle) and I employ a beveled gear and pinion in cooperation with each other, the latter having an eccentric element projecting outward from it that engages with an eccentric element extending inward from the edge of the gear.

I prefer to carry out my invention and accomplish the divers objects thereof in substantially the manner hereinafter fully described and as more particularly pointed out in the claims, reference being now had to the accompanying drawings that form a part of this specification.

In the drawings:

Figure 1 is a vertical elevation of my invention, showing the supporting structure or housing attached to a car end-sill.

Figure 2 is a top plan of the structure as positioned in Figure 1 with the housing removed for clearness.

Figure 3 is a vertical elevation of the gearing viewed from the right side of Figure 1.

Figure 4 is a vertical elevation from the same view-point as Figure 3 with the gear elements advanced to a position where the pinion has engaged with the gear just after the initial take-up movement has been completed.

Figure 5 is a vertical elevation of the structure at right angle to Figure 4 and in

the same relative positions as regards the respective gear elements.

Figure 6 is a top plan similar to Figure 2 showing a modified form of my invention.

Figure 7 is an elevation of the structure illustrated in Figure 6, and showing the large gear element in side elevation.

The drawings represent a typical or preferred form of my invention and are in a sense merely schematic for the purpose of illustrating the principles of the structure. So far as practicable I have employed similar reference character to designate like parts wherever they appear throughout the several views.

In the drawings 10 designates a channeled end sill of a railway car to which the support or housing for the gearing is secured. This housing preferably consists of a plate 11 that is vertically disposed against the web 15 of the sill and is provided with a lateral horizontal flange 12 that projects under and is secured to the lower flange of the sill. An arm 13 projects from the plate 10 and is provided with a vertically bored bearing boss 14 through which the brake shaft or mast 15 passes, and below flange 12 there is an oppositely extended bracket member 16 to the outer end of which a removable bearing boss 17 is secured that has a vertical bore aligning with the bore of the upper boss 14 to receive and support the lower end of the brake mast 15. The pinion or driving element of the gearing is secured to the mast between the bosses 14 and 17. In order to provide stability to the housing there are provided reinforcing pieces 18 and 19 that extend horizontally in opposite directions from the boss 14 and then downwardly, the piece 18 being connected with the outer portion of bracket member 16 and the piece 19, terminating substantially opposite the same and is provided with a bearing 20 for the spindle 21, the axis of which is horizontal and at a right angle to brake mast 15. Opposite boss 20 the housing is provided with an upstanding flange 22 that is bored in alignment with the bore in boss 20 to receive the adjacent end of the spindle 21 and mounted on this spindle is the pulley or drum 23, upon which the usual brake take up or pull chain is wound, and also the driven member of the gearing.

The driven member of the gearing consists of a pinion 24 secured to the brake mast 15.

15 and provided with beveled teeth. As seen in the drawings this element 24 is a complete beveled pinion, and its conical hub 25 is elongated towards the apex so that certain 5 of the teeth may be lengthened in the manner shown in Figures 1, 3, and 4. I provide an eccentric or cam-element in the form of a convolute of scroll flange or arm 26 the edge of which is provided with gear teeth 27 one 10 or more of which merge into and form the elongated tooth or teeth on the hub 25 of the pinion. This flange or eccentric gear member is not straight but it is bowed slightly in a downward direction as will be noted in 15 Figures 1 and 4, the purpose of which will hereinafter be pointed out.

The driven member of the gearing consists of a segmental gear 28 or concentrically curved toothed rack the teeth of which are 20 beveled so as to mesh with the teeth of the beveled pinion 24. This gear element is preferably two-thirds of a complete concentric gear and it is connected to its hub 29 by radial and bowed spokes 30, so that the 25 same is dished and presents a concavo-convex appearance. An eccentric flange 31 extends from one end of the row of teeth comprising the concentric or segmental gear portion which flange is provided with teeth 30 32 that are adapted to mesh with the teeth 27 on the eccentric flange of the pinion. The curve of the flange 31 is developed somewhat upon the form of a scroll or convolute and conforms generally to the curvature of the 35 scroll flange 26 of the driving pinion or gear element. This flange 31 also conforms in shape to the bulged or dished sectional shape of spokes 30 and as the flange is below the teeth of the pinion so also the flange 40 31 is slightly offset with respect to the spokes, thus permitting the flange 26 to pass within the inner circumference of the gear element 28 during the continued rotation of the pinion after the initial take-up has been 45 completed. (See Figure 5.)

It will be noted the shape and arrangement of the teeth on the respective gear elements is such that two scroll or convolute gears are provided that are intermeshed and 50 rotate upon axes at right angle to each other. When the gear elements are mounted on a railway car for the operation of the brake, in the manner herein illustrated, parts are positioned as seen in Figures 1, 2, and 3, with 55 the end or outer-portion of the flange 26 engaging with inner portion 31. The mast is then rotated clockwise and a slight turn rotates the large or driven gear element a third of a revolution or more quite rapidly, which 60 is sufficient under ordinary conditions to wind up the slack in the pull chain. After the teeth on the flanges have engaged throughout the length the teeth of the pinion element will be engaged with the teeth on 65 the gear element and the driven member will

then be actuated at a slow speed, but at a greatly increased power, so that the brake may be applied to the wheel with considerable friction.

The principles I have above described may 70 be embodied in a structure that is partly gear teeth and partly a cam groove or cam pin, as illustrated in Figures 6 and 7 of the drawings.

The structure hereinbefore described is 75 further exemplified in Figures 6 and 7 of the drawings, wherein the concentric elements of the gears are substantially the same as those previously described, but the eccentric elements of the respective gears are modified although they are adapted to perform the same functions as the eccentric portions of the gears shown in Figures 1 to 5. Referring now to Figures 6 and 7 of the drawings, the driving pinion has beveled teeth 80 40 and from the hub of the pinion there extends a radial and slightly bowed flange or arm 41, which has a lateral projection or pin 42 that is eccentric to the pinion and rotates therewith. The large or driven gear has 85 beveled teeth 43 that are provided along approximately two-thirds of its circumference, and the remaining portion of the gear element is plain and untoothed, as seen in Figure 7 of the drawings. The spokes 44 of 90 the large gear extend radially from the hub 45 and are bowed so that the gear element is dished or concavo-convex in the same manner as the driven gear element of Figures 1 to 5 inclusive. In order that there shall be 95 a co-operation between the arm and pin of the driving element and the driven gear member the latter is provided with a cam-groove 46, that is surrounded by a bead or 100 web 47 projecting preferably from one of the spokes 44. It will be noted the groove 46 extends inwardly towards the center or hub of the driven gear element so that, when the pin 42 is operating in said groove, the nearer the pin is to the center of the driven 105 gear element the faster the latter will be actuated by the driving gear element. In its initial or starting position the pin 42 will be at or adjacent the inner end of the groove 46 which is nearest the center of the driven 110 gear element and as the driving gear element is rotated in the proper direction the pin 42 moves outwardly in the groove and as the pin moves out of the groove 40, the teeth of 115 the driving gear element will mesh with the first teeth 43 of the driven gear element and thereafter the pinion and gear will operate in the customary manner with the latter at a reduced speed but with increased power. It will be understood that in the initial position and during the initial movement of the 120 element the teeth 40 of the driving element will be opposite the blank or untoothed portion of the driven element and it will also be noted that the position and the curvature 125 130

of the arm and the spokes of the elements permits the former to clear the latter during the subsequent operation of the structure. The operation of the structure illustrated in Figures 6 and 7 of the drawings is substantially the same as that disclosed in the other views of the drawings, because of the fact that the curved arm and pin have been substituted for the curved flange and teeth of the first described and the groove has been substituted for the inwardly extending flange and teeth of the driven element of the first-described structure.

What I claim is:—

- 15 1. A gearing comprising two gear elements disposed with their axes at an angle to each other, one of said elements being of segmental form and provided with an eccentric extension arranged in a spiral, the other element being a complete gear, and a spiral segmental flange extending from said complete gear for engagement with the eccentric extension of the other element.
- 20 2. A gearing comprising two gear elements rotatable upon axes at right angle to each other, one of said elements consisting of a segmental gear and a toothed member extending in a convolute inwardly and in a spiral from one end of said segmental gear, the other element consisting of a beveled pinion and a toothed flange extending outwardly from the hub thereof for engagement with the toothed member of the other element.
- 25 3. A gearing comprising two gear elements that are rotatable upon axes at right angle to each other, one of said elements consisting of a segmental gear and a toothed extension thereof that continues inwardly in a spiral towards the axis of said gear, the other element consisting of a beveled pinion and a toothed flange continuing in a spiral therefrom and beyond the teeth of said pinion and beyond the plane of said segmental gear for engagement with the toothed extension of the latter.
- 30 4. A gearing comprising a segmental gear, a toothed extension thereof the teeth of which continue from one end of said segmental gear and are disposed in a spiral towards the axis of said gear and in a different form than the latter, and a gear element rotatable at a right angle to said segmental gear and having parts that engage

respectively said gear and the toothed extension. 55

5. A gearing comprising a driving and a driven element, said driving element consisting of a pinion and a toothed spiral flange extending therefrom that is curved longitudinally, and said driven element consisting of a segmental gear disposed with its axis at an angle to the axis of said pinion with which it engages and a spiral gear member extending within the diameter of said segmental gear to be engaged by the spiral flange of the driving element. 60

6. A gearing comprising a drive-member and driven-member, the driven-member consisting of a segmental gear and a non-concentric element, and the drive-member consisting of a pinion and an element adapted to coact with said non-concentric element, the axes of rotation of said members being fixed and at an angle to each other. 65

7. A gearing comprising a drive-member and a driven-member, the driven-member consisting of a segmental gear and an element extending inwardly towards the axis of the gear, and the drive-member consisting of a pinion and a lateral element adapted to coact with the inwardly extending element of the other member, the axes of rotation of said members being fixed and at an angle to each other. 70

8. A gearing comprising a drive-member and a driven-member, the driven-member consisting of a segmental beveled gear and an element extending inwardly from the periphery of the gear towards the axis thereof, and the drive-member consisting of a beveled pinion engageable with said segmental gear and a lateral element extending outwardly from said beveled pinion and adapted to intermittently engage the inwardly extending element of the driven-member whereby to alter the speed of rotation of the driven-member, and shafts upon which the respective members are mounted, the axes of rotation of said shafts being at 75 an angle to each other and the planes of rotation of said drive and driven-members being present. 90

Signed at Chicago, in the county of Cook, and State of Illinois, this 15th day of October, 1925. 105

FRED MATHEWS.
